(57) **CLAIM**

The ornamental design for a watch with pulse sensor, as shown.

DESCRIPTION

The claimed watch with pulse sensor is a small portable timepiece with the function of measuring pulse rate.

FIG. 1 is a front elevational view of a watch with pulse sensor showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

FIG. 7 is a perspective view thereof.
